UNITED STATES PATENT OFFICE.

WILLIAM O. WAYMAN, OF CHICAGO, ILLINOIS, ASSIGNOR TO CRANE BROTHERS MANUFACTURING COMPANY, OF SAME PLACE.

LUBRICATOR

SPECIFICATION forming part of Letters Patent No. 296,657, dated April 8, 1884.

Application filed August 13, 1883. (No model.)

To all whom it may concern:

Be it known that I, WILLIAM O. WAYMAN, residing at Chicago, in the county of Cook and State of Illinois, and a citizen of the United States, have invented new and useful Improvements in Lubricators, of which the following is a full description, reference being had to the accompanying drawings, in which—

Figure 1 is a side elevation; Fig. 2, a vertical section; Fig. 3, a detail, partly in section, showing the driving-shaft and lifting devices; Fig. 4, a detail showing the plunger, with its opening for the passage of the oil; Fig. 5, a detail showing a modification in the form of lifting devices.

The object of this invention is to construct a pump for automatically passing oil or other lubricant from the receptacle for lubricating steam-cylinders and other devices; and its nature consists in the several parts and combinations of parts hereinafter specifically described, and pointed out in the claims as new.

In the drawings, A represents a cylinder of glass, forming the body or main portion of the receptacle for the oil.

B is a metallic cap having a rim or flange, b, around its periphery, and having a suitable opening closed by a plug, a, for filling the receptacle A; C, a metallic cap having a rim or flange, c, around its periphery. The cylinder A is located between the caps B C, and in the rims or flanges b c, and is held in position by such rims or flanges and the caps.

D is a stand having a hollow interior, and as shown, the cap C is formed with or is a continuation of the stand D.

E represents arms extending from the interior of the stand D at the upper end, to form supports for a plug.

F is the plug, located centrally of the stand D and cap C, and having a central opening to receive the plunger, and a smaller opening leading from the plunger-opening to the end of the plug, and closed by a valve, f, as shown in Fig. 2.

G is the plunger, having a transverse opening, d, leading from its exterior to an interior opening, e, which opening e extends longitudinally through the plunger, and is closed

at the end of the plunger by a valve, e', which valve and the end of the plunger are located in the opening therefor in the plug F, and between the end of the plunger and the end of the opening in the plug F is left a space to form a chamber, e'', when the plunger is at 55 the limit of its upward movement, as shown in Fig. 2.

H is a ring having on one end or side a flange, h, and from this end or side extends out the plunger G, the ring and plunger, as shown, 60 being formed together, but may be made separate and attached one to the other in any suitable manner, if desired. The opposite end or side of the ring H in line with the plunger G is provided with a pin, H', which enters an 65 opening in a boss at the center of the base-plate, and forms a guide to maintain the plunger in a direct line of movement.

I is an eccentric located to engage the interior face of the ring H and give the plunger 70 G its required movement.

J is a shaft on which the eccentric I is located or mounted. One end of this shaft enters a sleeve or second shaft, J', on the end of which adjacent to the cam I is an eccentric, I', 75 arranged to engage the flange or plate h of the ring H.

K K' represent a stuffing-box for the shaft or sleeve J', the portion K having a screw-threaded end to enter a screw-threaded opening in the stand D, and having a central screw-threaded opening to receive the screw-threaded body of the section K'. This stuffing-box K K' forms a bearing for the shaft or sleeve J', and the object of entering the end of the shaft J 85 into the secondary shaft or sleeve J' is to provide a bearing-surface on that side of the ring H to support and maintain the shaft and operating-eccentric in position.

L is a locking slide or clutch located around 90 the sleeve or shaft J' at the end of the stuffing-box K K', the portion K of the stuffing-box having serrations or teeth i, with which serrations or teeth i' on the slide or clutch L engage, as shown in Fig. 1; and the sleeve or 95 clutch L is connected with the shaft or sleeve J' by a spline or key, j. (Shown by dotted lines in Fig. 3.) The end of the shaft or sleeve J'

is provided with a flange or rim, *J*", having a head to receive a wrench or other device, by which the sleeve can be turned to adjust the eccentric *I* in different positions in relation to the ring *H* to regulate the throw of the plunger, and between this collar or arm *J*" and the end of the sleeve *L* is a spring, *k*, for holding the sleeve in engagement with the stuffing-box section *K*. The shaft is turned by pulling the sleeve *L* back to disengage the teeth *i i'*, and the spline or key *j*, leaving the shaft or sleeve *J*' free to be turned in the stuffing-box.

M M' represent a stuffing-box for the shaft *J* on the opposite side of the eccentric *I*, the section *M* of the stuffing-box having a screw-threaded end to enter the stand *D*, and the section *M'* screwing onto the section *M*.

N is a wheel or pulley for a belt, by means of which the shaft is given a rotary movement; but instead of using a pulley or wheel, a rock-arm may be provided for giving the shaft a rocking movement; or the shaft may be otherwise operated to cause the eccentric *I* to act on the ring and give the plunger *G* the required movement. The plunger is made to enter the opening in *F* by the action of the cam *I* on the interior of the ring *H*, and is withdrawn as the eccentric is moved around by means of the spiral spring *g*, located around the plunger between the plate *h* and the end of *F*, as shown in Fig. 2.

O is the base-plate, having a screw-threaded flange, *O'*, to which the end of the stand *D* is screwed; but the connection between the base-plate and the stand might be made in some other suitable manner.

P is a chamber connected by a collar, *P'*, with the end of a tube, *G'*, which tube passes through the receptacle *A*, one end being screw-threaded, and connected thereby to the end of the plug *F*, leaving a sufficient space between the end of the plug and the end of *G* to form a chamber, *f'*, for the valve *f* in the end of the plug to operate, and the other end of the tube *G'* is screw-threaded and passes through a screw-threaded opening in the center of the cap *B*, forming the means for bringing the cap down to hold the cylinder *A* in place. The collar *P'* is located around the end of the tube *G'*, which passes beyond the cap *B*, and in the end of the tube *G'* is located a valve, *f*³, the chamber for which, *f*⁴, is formed in the end of the tube *G'*, as shown in Fig. 2. The tube *G'* has a central longitudinal opening, *f''*, which, when the parts are together, comes in line with the opening *e* of the plunger *G*, to allow the oil to pass through the tube *G'*. The chamber *P* is provided with a stuffing-box, *P''*, for connection with a steam-pipe.

Q is a window, of glass or other suitable material, in the chamber *P*, to allow inspection of the interior of such chamber.

R is a glass tube located within the chamber *P*, and held in position by suitable stuff-

ing-rings, *l*, in which tube *R* a nozzle, *m*, enters from the collar *P'*, the opening in the nozzle being in line with the opening in the tube *G'*, as shown in Fig. 2.

The operation is as follows: The rotation of the shaft *J* or other movement of such shaft causes the eccentric *I* to act on the ring *H* and operate the plunger. The downward movement of the plunger causes oil to enter through the opening *d* from the chamber in the stand *D*, which oil passes up in the opening *e* and out through the chamber of valve *e'*, the latter dropping down to place as the plunger is again raised, and from the chamber *e''* the oil passes, by the rising of the valve *f*, into the chamber *f'*, from which chamber it enters the opening *f''* in the tube *G'*, to pass through the nozzle *m* and through the tube *R* to the steam-cylinder to be lubricated. The oil is forced up through the valve in the plunger at each stroke, gradually raising the oil through the tube in the oil-receptacle, passing it through the valve at the end of such tube, forcing it through the nozzle at the end of the tube, to pass therefrom through the sight-tube, such movements of the oil being effected through the strokes of the plunger, each stroke passing a given quantity of oil, the quantity first passed being forced forward by the next succeeding quantity, and so on. The valve *f*³ is provided to prevent a return of the oil after it has passed through the tube *G'* and into the chamber *f*⁴, to enter the nozzle *m*; but this valve *f*³ may be dispensed with, if desired.

Instead of using a ring, *H*, for the eccentric to act on, a disk, *S*, may be used, the eccentric bearing against the bottom of the disk, as shown in Fig. 5, and the disk fitting and having its bearing against the side of the chamber in the stand *D*.

What I claim as new, and desire to secure by Letters Patent, is—

1. The combination, with a receptacle, *A*, and a stand, *D*, of a hollow lifting-plunger, *G*, and devices for operating the same, located and operating within the oil-receptacle and its base, for passing oil or lubricant from the receptacle, substantially as and for the purpose specified.

2. The receptacle *A* and stand *D*, in combination with a hollow lifting-plunger, *G*, eccentric *I*, and shaft *J*, located and operating within the oil-receptacle and its base, for reciprocating the plunger to raise and pass the oil from the receptacle, substantially as specified.

3. The receptacle *A*, stand *D*, hollow plunger *G*, eccentric *I*, and shaft *J*, in combination with a plug, *F*, tube *G'*, and suitable valves for lifting and controlling the oil, substantially as and for the purpose specified.

4. The receptacle *A*, stand *D*, plug *F*, hollow plunger *G*, spring *g*, eccentric *I*, and shaft *J*, in combination with the tube *G'*, valve for

controlling the passage of the oil, and chamber P, substantially as and for the purposes specified.

5. The chamber A, stand D, plug F, hollow plunger G, spring g, eccentric I, and shaft J, in combination with the tube G', valve for controlling the passage of the oil, nozzle m, chamber P, and pipe R, substantially as and for the purposes specified.

6. The receptacle A, stand D, plug F, and 10 plunger G, in combination with the eccentric I I', shaft J, and sleeve J', substantially as and for the purpose specified.

WILLIAM O. WAYMAN.
